(57) **CLAIM**

The ornamental design for a hydroponic plant rack apparatus, as shown and described.

DESCRIPTION

FIG. 1 is a perspective view of a first embodiment of a hydroponic plant rack apparatus, showing my new design in an assembled configuration;

FIG. 2 is another perspective view thereof;

FIG. 3 is a top plan view thereof;

FIG. 4 is a bottom plan view thereof;

FIG. 5 is a front plan view thereof;

FIG. 6 is a rear plan view thereof;

FIG. 7 is a left side elevation view thereof, with the right side elevation view being a mirror image thereof;

FIG. 8 is an exploded perspective view of FIG. 1, showing the apparatus having a pot and a spacer in a disassembled configuration;

FIG. 9 is a top plan view of FIG. 8, shown with the exploded pot and spacer offset to reveal the tops of both portions;

FIG. 10 is a bottom plan view of FIG. 8, shown with the exploded pot and spacer offset to reveal the bottoms of both portions;

FIG. 11 is a front plan view of FIG. 8;

FIG. 12 is a rear plan view of FIG. 8;

FIG. 13 is a left side elevation view of FIG. 8, with the right side elevation view being a mirror image thereof;

FIG. 14 is a perspective view of another embodiment of the hydroponic plant rack apparatus, showing a plurality of spacers stacked and assembled;

FIG. 15 is another perspective view; of FIG. 14;

FIG. 16 is a top plan view of FIG. 14;

FIG. 17 is a bottom plan view of FIG. 14;

FIG. 18 is a front plan view of FIG. 14;

FIG. 19 is a rear plan view of FIG. 14;

FIG. 20 is a left side elevation view of FIG. 14; with the right side being a mirror image thereof;

(Continued)

FIG. 21 is a perspective view of another embodiment of the hydroponic plant rack apparatus, showing a plurality of spacers and pots stacked and assembled, and being coupled to an environmental pipe;

FIG. 22 is another perspective view of FIG. 21;

FIG. 23 is a top plan view of FIG. 21;

FIG. 24 is a bottom plan view of FIG. 21;

FIG. 25 is a front plan view of FIG. 21;

FIG. 26 is a rear plan view of FIG. 21;

FIG. 27 is a left side elevation view of FIG. 21, with the right side elevation view being a mirror image thereof; and, FIG. 28. Is a section view of FIG. 21, taken in the direction of line 28-28.

The broken lines illustrate environment that forms no part of the claimed design.
